UNITED STATES PATENT OFFICE.

JOHN E. ALLSTEADT, OF HASTINGS, NEBRASKA.

TANK-HEATER.

1,397,831.

Specification of Letters Patent.

Patented Nov. 22, 1921.

Application filed March 4, 1920. Serial No. 363,358.

To all whom it may concern:

Be it known that I, JOHN E. ALLSTEADT, a citizen of the United States, residing at Hastings, in the county of Adams and State 5 of Nebraska, have invented new and useful Improvements in Tank-Heaters, of which the following is a specification.

This invention relates to tank heaters and particularly to heaters for heating the water 10 contained in exposed stock watering troughs, tanks and the like.

The main object of the invention is to provide a simple, reliable and efficient type of heater which is rapid in its heating action and which is adapted to be swung out of the tank and inverted to enable the fuel ashes to be readily dumped.

A further object of the invention is to provide a tank heater which is simple of 20 construction, economical of manufacture and installation and in the use of fuel, and insures efficient combustion of the fuel and distribution of heat throughout the body of the water.

25 The invention consists of the features of construction, combination and arrangement of parts, hereinafter fully described and claimed, reference being had to the accompanying drawing, in which:—

30 Figure 1 is a vertical longitudinal section through a water tank and water heater embodying my invention, showing fragmentarily in dotted lines the heater swung outward to inverted position.

35 Fig. 2 is a top plan view thereof, with a portion of the heater cover broken away.

Referring to the drawing, 1 designates a water containing tank or trough, used for stock watering or other purposes, which tank 40 is open at its top and includes in its construction a front wall 2. Suitably secured to the wall 2 are spaced uprights 3 extending at their upper ends to a suitable point above the level of the top of the tank. Pivotally secured at their forward ends, as at 4, to the uprights 3, are supporting bars 5 fixed to and carrying the heater 6.

The heater 6 may be made of oval or other suitable form and of sheet metal or other 50 suitable material, and comprises a body rigidly fastened at the upper portions of its sides to the bars 5 and adapted for swinging movements with said bars 5 between normal and dumping positions, as hereinafter described. In the normal position of the heater, the bars 5 rest at their forward ends

upon the upper edge of the wall 2 and extend over the top of the tank, thus supporting the heater 6 in a pendent position within the tank, the heater being submerged in the 60 body of water in the tank and serving to heat the same to a predetermined temperature.

Arranged within the heater body 6 is a grate 7, resting removably upon suitable 65 supports 8. This grate subdivides the interior of the heater into an upper combustion chamber 9 and a lower ash pit or receptacle 10, the grate being adapted to support a body of fuel 11 of suitable character for 70 heating the interior thereof and effecting the heating of the water within the tank to the desired temperature. A cover 12 is provided for normally closing the top of the heater, and this cover is provided with an 75 opening 13 for the discharge of the smoke and other products of combustion, said opening communicating with a chimney 14 having a controlling damper 15 therein whereby the draft and the discharge of the products of combustion may be regulated. The 80 cover 12 may be removed whenever it is desired to invert the heater for the discharge of the ashes and other unconsumed particles of fuel, and is placed in position to close the 85 top of the heater when the latter is submerged in the water in the tank for use.

The ash pit 10 communicates at its rear end with the lower end of an air supply conduit or flue 16 which extends to the level 90 of the top of the heater and is provided at its upper end with one or more air inlet openings controlled by a suitable damper 17, whereby the supply of air to the ash pit for upflow through the grate may be regulated and controlled as desired. Disposed in the rear portion of the ash pit is an inclined deflector 18 arranged in the path of flow of the air entering the same from the flue 16, said deflector serving to deflect the 95 air downward at its point of inlet and cause it to travel upwardly and longitudinally beneath the grate, thus distributing the supply of air throughout the entire area of the grate. By this means the body of air instead of flowing upward at the rear of the grate is uniformly distributed throughout the mass of the body of fuel resting on the grate, thus promoting combustion and increasing the efficiency of heating action of 100 the heater.

Water heating pipes or tubes 19 are ar-

ranged within the combustion chamber 9 at a suitable point above the level of the grate 7 and in the path of the flames and heated products of combustion rising therefrom. These pipes or tubes extend from side to side of the heater 6, and open through the side walls thereof, said pipes or tubes thus being in communication with the body of the water in the tank 1 for the 10 flow of the water therethrough. It will thus be understood that the body of water will be heated both by radiation and the conduction of heat units through the wall of the body of the heater, as well as by the tubes or pipes 19 in the flow of the water therethrough. These tubes or pipes 19 are arranged in an inclined position, one end of each tube lying at a higher elevation than the other, so as to properly provide for the 15 inlet of the relatively cool water at one end of the tube and the discharge of the heated water at the opposite end of the tube, resulting in a circulation of the water throughout the tank. By this means of heating the 20 body of water by radiation and conduction from the submerged tank, as well as by the conducting pipes or tubes, the water contents of the tank may be rapidly heated with the consumption of a minimum amount 25 of fuel, thus producing a type of heater which is simple of construction and adapted to be used for heating purposes at a comparatively low cost. The tubes or pipes 19 are arranged in spaced relation, not only to 30 provide for the upflow of the products of combustion, but also to permit of the passage of fuel between them in supplying fresh fuel to the grate, and further to permit of the discharge of the ashes and other residue 35 40 when the heater is inverted for the discharge of the consumed portions of fuel.

Pivottally connected at their rear ends to the sides of the heater 6, near the top thereof, as indicated at 20, are arms 21, which extend forwardly from the pivotal points 20 and outwardly beyond the line of the front wall 2 of the tank between the uprights 3, said arms 21 being connected at their forward ends by a cross bar or handle 22. The 45 50 uprights 3 and forward ends of the arms 21 are provided with openings to receive fastening pins 23, employed for holding the arms 21 in the normal position shown in Figs. 1 and 2. In this position it will be 55 evident that the arms 21 will act as braces or stays coöperating with the bars 5, resting at their forward ends on the upper edge of the wall 2, to stably support the heater 6 submerged within the water contained in 60 the tank. In this position of the heater, and upon removal of the cover 12, fresh fuel may be supplied to the grate to maintain the heater in operation, and the combustion of the fuel and degree of heat generated may 65 be regulated by adjusting the dampers 15 65 and 17. In practice, it will be understood that the cover 12 may be hinged to the heater body to permit it to be conveniently opened and closed, or it may be provided with a suitable opening therein, and a closure for said opening, whereby fuel may be introduced without the necessity of removing the cover or of varying its position. When, however, it is desired to discharge the ashes and clean out the heater, this may 70 75 be readily effected by removing the fastening pins 23 and pulling upon the handle 22 so as to draw the arms 21 forwardly, the parts 21 and 22 thus forming a bail-handle and coacting with bars 5 to form a draft 80 element, whereby the heater 6 may be elevated and swung forwardly on the pivot member 4 to an inverted position, upon removal of the cover 12. In this position the ashes and other unconsumed products of 85 combustion will be discharged by gravity upon the floor or in any other suitable receptacle, after which the heater may be swung backward into position for further use in the tank and secured in such position 90 by replacing the fastening pins 23, as will be readily understood. As stated, the grate 7 may be made removable to facilitate the discharge of the ashes and unconsumed products of combustion if such is necessary, or 95 it may be made in two sections for the purpose, or the grate bars may be made sufficiently spaced to permit of the discharge of the ashes therethrough without the necessity of removing the grate. By however 100 making the grate removable it will of course be understood that all portions of the interior of the heater may be reached and cleaned with greater facility, and provision also made for cleaning the air flue and heating tubes or pipes 19 with a greater degree 105 of ease and convenience.

Having thus fully described my invention, I claim:

1. In a tank heater, the combination of a 110 water containing tank, a heater pivotally supported therein, and means for swinging the heater outwardly from the tank to an inverted position.
2. In a tank heater, the combination of a 115 water containing tank, a heater disposed therein, said heater having heating means therein and water heating tubes extending from side to side of and through said heater, means for pivotally supporting the heater 120 within the tank, and means for swinging the heater outwardly from the tank to an inverted position.
3. In a tank heater, the combination of a 125 water containing tank, a heating drum 125 therein, pivoted bracket members supporting the drum, a draft element for swinging the drum externally of the tank to an in-

verted position, and means for locking said lever mechanism to hold the drum suspended within the tank.

4. In a tank heater, the combination of a tank, a pair of spaced uprights secured to and extending upwardly from the tank, supporting bars pivoted to said uprights, a heating drum carried by said bars and normally submerged in the water contained in the 10 tank, a handle pivoted to the tank and operative for swinging the tank outwardly to an inverted position, and means for locking said handle to the uprights for coöperation with the supporting bars to hold the drum 15 suspended within the tank.

5. In a tank heater, the combination of a water containing tank, a heater arranged within the tank and comprising a drum open

at its top and having a grate therein forming an upper combustion chamber and an 20 ash pit, a down draft air flue communicating with one end of the ash pit, an inclined deflector arranged in such end of the ash pit for deflecting the air against all portions of the underside of the grate, a damper 25 controlling the influx of air to the flue, inclined water heating tubes extending through the combustion chamber from side to side of the drum and opening through the sides of the latter, means for pivotally supporting the drum, and means for swinging the drum on its pivotal support from a pendent position within the tank to an inverted position outside the tank. 30

In testimony whereof I affix my signature.

JOHN E. ALLSTEADT.
